UNITED STATES PATENT OFFICE

2,512,111

CRADLE EGG CARTON

Clement L. Monahan, Chicago, Ill.

Application January 23, 1947, Serial No. 723,757

2 Claims. (Cl. 229-28)

This invention relates to an improved receptacle especially adapted for receiving eggs therein.

An object of this invention is to provide a device of the character described so constructed as to be inherently shock absorbing, thereby protecting the eggs therein against breakage.

Another object of this invention is to provide a device which is flexible in nature to further insure protection against shock and breakage.

A further object of this invention is to provide means for releasably connecting the elements thereof, and consequently rendering the device easy to fabricate and dismantle.

A still further object of this invention is to provide a device composed entirely of sheet material.

Another object of this invention is to provide an extremely economical, satisfactory and improved egg container.

Other objects and features of novelty shall be specifically pointed out or shall become readily apparent to those skilled in the art, in following the description the preferred embodiments of the instant inventive concept, illustrated in the accompanying drawings, wherein:

Figure 1 is a perspective view of the first embodiment of the instant invention, showing the same in assembled form;

Figure 2 is a plan view of the invention disclosed in Figure 1, the cover being removed in order to show the egg contacting points thereof;

Figure 3 is a plan view of a web member used in conjunction with both of the illustrated embodiments of the present invention;

Figure 4 is an elevational view of the cover and bottom strip forming part of the instant invention;

Figure 5 is a plan view with parts broken away, of a second embodiment of the instant inventive concept;

Figure 6 is a side elevational view of the instant invention;

Figure 7 is an end view of the second embodiment of the present invention;

Figure 8 is an end view of the second embodiment showing the construction of the side opposite that shown in Figure 7;

Figure 9 is an elevational side view of the spacer used in conjunction with the second embodiment of the instant invention;

Figure 10 is a plan view of a web member used with either embodiment of the present invention, and

Figure 11 is a plan view of the strip member

adapted to be used in the second embodiment of the invention.

Referring now in detail to the illustrations of the preferred embodiments of the present invention, like reference characters are used to indicate similar parts throughout.

The invention is constructed of a sheet material such as cardboard or other specially prepared or treated paper material. The securing means for the various components comprises solely a novel series of slots, tabs and folds. A substantially rectangular sheet member 10 is provided with a plurality of arcuate slots 12 at the bottom longitudinal edge thereof and similar slots 14 having cuts 16 centrally thereof, at the top longitudinal edge of the said member 10. A keeper, in the form of a slot 18 is provided at each end of the said rectangular or web member 10. A pair of the above described web members 10 are interlockingly secured together after creasing the same along the lines 20, shown in Figure 3. In securing the said pair of webs 10, the slots 16 of each web are received appropriately. The resulting structure is clearly shown in Figure 2 and an egg is shown therein. It is noted that the web members are so folded that the egg receiving portion is generally octagonal in shape. This construction provides eight bearing surfaces adapted to engage the periphery of an egg. The ends of the said webs 10 are secured by interlocking the end slots 16 of each web.

A substantially rectangular strip 24 is provided with identical folds 26 at both ends and in the center thereof. Two tabs 30 are cut into each fold. In the material between folds is a plurality of longitudinal bent portions or folded portions 32. A first fold 26 is secured to the end of the said web member 10 by inserting the said tab 30 into the hereinbefore mentioned slots 18. The body portion of the said strip is then placed under the said web and the marginal folds 32 are slipped into the said slots 12, described above. The second fold 26 is secured to the second end of the said web by means of the said tab 30 and the strip is curved or bent over the top portion of the said web. The marginal folds in the top portion of the said strip are then releasably tucked in the appropriate slots 14 and the final tab bearing fold 26 is secured on top of the said first fold 26. A convenient tongue 34 is formed in the last mentioned fold 26 for opening the said egg receptacle.

This carton provides ventilated and all around protection against shock and breakage to each

egg therein. It is noted that ten bearing surfaces are provided for each egg thereby reducing shock transmission and practically holding each egg in suspension. Further protection to each individual egg against shock and breakage is provided by the carton's flexibility and plurality of interlocking joints affording proper resilience to the device. This feature is necessary, especially in view of the variation in sizes of eggs.

Referring now to the second embodiment of the instant invention, an egg container capable of holding a larger number of eggs is disclosed. Web member 10 similar in configuration, but larger than the above described web, is provided. A pair of the said webs 10 are joined exactly as has been described and the strip 36 (seen in Figure 9) is slid in the plane of the longitudinal center of the said web 10. As is noted suitable guide ways 38 are cut into the said member 36 for this purpose. The strip member 24, seen in Figure 11, is then secured to the said web as described hereinbefore. As is apparent from an inspection of Figure 11 the only material difference between the strip shown in this figure and the strip shown in Figure 4, is in size and consequently the location of the tabs 30.

The operation of each embodiment illustrated in the drawings, is identical. By grasping the tongue 34 and pulling the same, the first fold 26 is released and the said marginal folds 32 are pulled out of their slots 14. The eggs in the container are now readily accessible. In breaking down the device the said strip is simply pulled a little further and consequently taken out of engagement with the web. The ends of the said web members are simply slipped apart as is each web slipped from interlocking engagement with each other.

It is now apparent that a simple and extremely inexpensive break-down egg carton is provided by this invention. Further, due to the extreme simplicity of the device, considerable time is saved in fabricating and dismantling the egg carton in use and reuse of the same.

While there has been described but preferred embodiments of the instant invention, it is apparent to those skilled in the art, that certain changes may be made herein including omissions and additions, without departing from the spirit of the invention. Accordingly, limitation is desired only in the scope of the following claims.

Having thus described the instant invention, what is claimed as novel and improved is as follows:

1. An egg container comprising a longitudinal strip, transverse folds in said strip to form a bottom, top and end section, a pair of web members intersecting each other at spaced intervals forming individual compartments, angularly inclined slots in said web members and opening through the marginal edges of said web members and releasably locked with the edges of said top and bottom, a crease extending longitudinally of said bottom and top and the material of said bottom and said top on one side of said crease extending at an angle to the remainder of the top and bottom to provide a plurality of bearing surfaces for articles retained in each compartment at the top and bottom thereof, and means at the ends of said web members and said end sections to releasably lock said end section and the ends of said web members together.
2. The combination of claim 1 and a plurality of transverse folds in said web members forming at least six sided compartments.

CLEMENT L. MONAHAN.
